(57) **CLAIM**

The ornamental design for a collapsible vertical roasting rack, as shown and described.

DESCRIPTION

FIG. 1 is a top perspective view of a collapsible vertical roasting rack showing my new design;

FIG. 2 is a right side elevational view thereof, the left side being a mirror image;

FIG. 3 is a front elevational view thereof, the rear being a mirror image;

FIG. 4 is a top plan view thereof; and,

FIG. 5 is a bottom plan view thereof.
